UNITED STATES PATENT OFFICE.

GUSTAV A. JAEGER, OF MORRISON, ILLINOIS, ASSIGNOR OF THREE-FIFTHS TO HATTIE JAEGER AND TWO-FIFTHS TO ELIZABETH JAEGER, OF MORRISON, ILLINOIS.

POCKET FOR POOL-TABLES.

1,192,902.

Specification of Letters Patent.

Patented Aug. 1, 1916.

Application filed November 8, 1915. Serial No. 60,330.

To all whom it may concern:

Be it known that I, GUSTAV A. JAEGER, a citizen of the United States, residing at Morrison, in the county of Whiteside and State of Illinois, have invented certain new and useful Improvements in Pockets for Pool-Tables, of which the following is a specification.

This invention relates to pockets for pool tables and has for its object to provide a construction which will facilitate the assembling of the several parts and cause them to be firmly held in place when assembled.

The invention is illustrated in the accompanying drawings and consists in certain novel features which will be hereinafter first fully described and then more particularly pointed out in the claims following the description.

20 In the annexed drawings: Figure 1 is a plan view of a pocket embodying my present improvements; Fig. 2 is a vertical section taken on the line 2—2 of Fig. 1; Fig. 3 is a section taken on the line 3—3 of Fig. 1; 25 Fig. 4 is a detail perspective view.

The pocket embodying my invention may be applied to the corner or to the side of a pool table but is illustrated in the accompanying drawings applied to the corner only. The pocket iron 1 is provided at its ends with studs 2 adapted to enter mortises in the rails of the table to support the iron in proper position. In the upper face of the iron and close to and concentric with the outer arcuate edge of the iron is a groove 3 to receive an outer edge portion of the liner leather 4 as clearly shown in Figs. 2 and 3. This liner is formed of heavy leather pressed into an arcuate shape and provided with an inner depending flange 5 which extends below the iron and over the band and serves as a cushion to receive the impact of the balls shot into the pocket. The liner is also provided with an outer depending flange 6 which enters the groove 3 and is held therein by screws or similar fastenings 7 inserted through the iron from the inner side thereof so as to engage the said flange 6 of the liner as shown most clearly in Fig. 3, the said

50 fastening devices being inserted before the inner flange of the liner is brought into place and are, consequently, covered by the said

inner flange of the liner and prevented from injuring the balls.

The outer portion of the iron 1 is extended below the main body thereof as shown at 8 and forms a depending arcuate rim adapted to coact with the band 9 in securing the pocket in position. The pocket consists of leather straps 10 which are brought together near their lower ends and secured around a stop 11 of any preferred form to form the bottom of the pocket and support the ball deposited therein. The shield or fringe 12 is provided near its upper edge with a series of slots 13 to receive the upper ends of the straps 10 and thereby hold the said straps in spaced relation, openings 14 being formed in the upper extremities of the pocket straps and registering with similar openings in the shield or fringe fitted over studs 15 on the band 9.

The studs 15 are illustrated as formed on the band 9, but it will be understood, of course, that they may be formed on the lower rim 8 of the pocket iron but, in either event, the slots 13 will be spaced in the same manner as the studs so that, when the ends of the pocket straps are inserted through the slots 13, they will be in position to fit readily over the studs and be supported by the same. The preferred construction is that illustrated with the studs formed on the band and it will be understood that after the shield and the pocket straps have been fitted on the studs, the band with the shield and the pocket will be brought into position concentric with and at the inner side of the rim 8 and then fitted close to said rim. Screws or similar fastening devices 16 are then inserted through openings provided therefor in the rim 8 to engage threaded openings in the band, as shown clearly in Fig. 3, to clamp the band to the rim and thereby secure the pocket and shield in position. The straps at the inner side of the pocket will be secured to the under side of the table in the usual or any preferred manner and will preferably be so secured as to be readily detached whenever repairs may be necessary.

It will be readily understood from the foregoing description, taken in connection with the accompanying drawings, that I

have provided a pool pocket of very simple conservative construction which may be very quickly fitted to a table and which will facilitate the renewal of the pocket straps or 5 fringe or liner.

Having thus described the invention, what is claimed as new is:

1. In a pocket for pool tables, the combination of a pocket iron having a body portion and a rim depending below the outer edge of said body portion, a band concentric with the inner side of said depending rim, studs bridging the space between the band and the rim, pocket straps hung on said 15 studs, a shield also hung on said studs, and means for securing the band to the rim.

2. In a pocket for pool tables, the combination of a pocket iron having a body portion and a rim depending from the outer edge of said body portion, a band disposed concentric with the inner side of said rim, spaced studs on said band, a shield hung on said studs and having a plurality of slots

disposed below the studs, pocket straps having their upper ends inserted through said 25 slots and engaging over said studs, and means for securing the band to said rim whereby to support the shield and pocket straps.

3. In a pocket for pool tables, the combination of a pocket iron having a body portion and a rim depending from the outer edge of said body portion, a band disposed below the body portion of the iron concentric with the said rim, studs bridging the 35 space between the said rim and the band, a shield hung upon said studs and having slots disposed below the respective studs, pocket straps inserted upwardly through the said slots, and fastening screws inserted through 40 the said rim and the shield to engage the band and thereby clamp the band to the rim.

In testimony whereof I affix my signature.

GUSTAV A. JAEGER.
